JOHN E. DAVIS, OF BROOKLYN, NEW YORK.

MEANS FOR TRANSFORMING INAUDIBLE OSCILLATIONS INTO AUDIBLE OSCILLATIONS.

Application filed August 14, 1925. Serial No. 50,159.

This invention relates to means for transforming inaudible sound oscillations of waves into audible sound oscillations or waves, and particularly adapted for use for connection in circuit with and influenced by an electric oscillation receiving circuit, and it is the primary object of the invention to provide an improved constructed and arranged transformer for this purpose to 10 greatly intensify or amplify the audio oscillations.

In transformers of this character as heretofore constructed it has been the practice to effect the transforming of the inaudible sound oscillations through a vibratory diaphragm by mounting said diaphragm in a casing having an air space or chamber at one side of the diaphragm only in communication with a sound emitting orifice or outlet in the casing to which outlet means is adapted to be connected to further amplify the audio oscillations transmitted by the diaphragm, and it is the principal object of the invention to provide a transformer for 20 this purpose wherein both sides of the diaphragm are open to the air chamber in communication with the sound emitting outlet of the casing.

It is a further object of the invention to provide a transformer of this character arranged with a pair of diaphragms adapted to be operated in unison with both sides of each diaphragm open to an air space or chamber in communication with the sound emitting outlet of the diaphragm carrying casing.

Other objects and advantages will herein-after appear.

The embodiment of the invention illustrated is particularly adapted for connection in circuit with an electric oscillation receiving circuit to transform electric oscillations into audio oscillations, and as comprising a casing with a pair of diaphragms arranged 40 therein with both sides of each diaphragm open to an air space or chamber which is in communication with a sound emitting outlet from the casing, with magnetic force generating means to influence the diaphragms in unison interposed between the diaphragms and adapted for connection in circuit with an electric oscillation receiving circuit, and said means including a pair of solenoid magnets with the diaphragms operatively positioned relative to the cores thereof, and a permanent magnet to the pole portions of

which the cores of the solenoid magnets are connected and the means for connecting said cores with the magnet also being adapted to mount the solenoid magnets and permanent magnet in the casing.

In the drawing accompanying and forming a part of this specification Figure 1 is a side elevation of my improved transformer of inaudible sound oscillations into audio oscillations.

Figure 2 is an end elevation looking at the right of Figure 1 with the end removed to show the arrangement and mounting of magnetic force generating means in the 70 casing.

Figure 3 is a cross sectional view taken on the line 3-3 of Figure 2 to show the mounting of the diaphragms in relation to their actuating means.

Figure 4 is a perspective view, partly broken away, of an end of the casing to show the arrangement of mounting a diaphragm thereon; and

Figure 5 is a detail view in perspective on an enlarged scale to show the connection of the cores of the solenoid magnets with the pole portions of the permanent magnet and the mounting of the solenoid magnets and permanent magnet in the casing.

In the embodiment of the invention illustrated there is provided a casing comprising a tubular member 6 having closures 7 and 8 removably connected to opposite ends of said member, as by arranging the two closures with an internally threaded peripheral flange to have threaded connection with the tubular member, one of said closures having a central sound emitting outlet 9 having a tubular throat piece 10 mounted therein with a bayonet slot 11 at the outer end to adapt the casing for the releasable connection of an amplifier, such as a horn, to amplify the sound emitted from the outlet 9. Each of the closures has lugs 12 circumferentially disposed in equidistant spaced relation about the same to extend radially inward from the closure flange in contiguous relation to the inner surface of the closures and each lug having a part 13 extending laterally into and in a direction parallel with the axis of the casing and arranged with screw threads on the inner wall. While three of these lugs are shown in the present instance a greater number may be employed if desired. These lugs constitute supporting seats for diaphragms 14 and 15. The diaphragms

are mounted on said seats by clamping the diaphragms between a pair of rings 16, 17, the ring 16 engaging the lugs and the ring 17 having screw threaded connection with the portions 18 projecting from the lugs.

The diaphragms are actuated or vibrated in unison by magnetic means adapted for connection in circuit with and influenced by an electric oscillation receiving circuit, 10 such as a telephone circuit or radio receiving circuit, said means comprising a permanent magnet 18 of split ring form and a pair of electro-magnets 19, 20, shown of the solenoid type and consisting of coils of wire 15 wound about spools on cores 21, 22 of magnetizable material by which the spools are carried. One end of each core is extended beyond the coil carrying spools and bent inwardly toward each other so that said end 20 of the cores arranged in opposed relation to the diaphragm 15 will be substantially centrally of said diaphragm. The opposite end of the core 21 is extended in a direction toward one pole of the permanent magnet to be electrically connected thereto and bent about the outer side of said magnet. The other end of the other core 22 is similarly extended for connection with the other pole portion of the permanent magnet. The 25 magnet cores 21, 22 are in effect pole pieces for and are secured to the permanent magnet by screws 23, 24 passing through openings in and from the exterior of the casing and openings in the ends of the magnet cores 30 bent around the permanent magnet and threaded into the latter, said screws also serving to mount and support the magnetic force generating means in the casing. The portion of the cores at the ends of the spools 35 opposite to the bent ends of the cores and intermediate the extended part thereof whereby they are connected to the permanent magnet are bent upon themselves in a direction toward each other and laterally of the 40 spools, as shown at 26, whereby said portion will be arranged substantially centrally of the diaphragm 14 and facilitate the attracting of the central portion of the diaphragm thereto. The permanent magnet is of smaller size than the casing to provide a space 45 between the magnet and casing.

By the arrangement of mounting the diaphragms upon the casing closures 7 and 8 there is provided an air space or chamber 55 at both sides of the diaphragm 15 which is in communication with the sound emitting orifice 9 of the casing, and an air space or chamber is also provided at both sides of the diaphragm 14 which is in communication with the sound orifice 9 through the space between the permanent magnet and casing wall. It will be obvious that as both sides of the diaphragm 15 are in open communication with the sound emitting orifice 60 9 enhanced or intensified audio oscillations

are transmitted from the casing outlet, and that these audio oscillations will be further enhanced and intensified by the arrangement of the other diaphragm 14 with both sides thereof in communication with an air space communicating with the outlet orifice 9.

By the arrangement of the threaded connection of the closures 7 and 8 with the casing member 6 and the mounting of the 75 diaphragms on said closures the diaphragm actuating means and the diaphragms may be variably adjusted relative to each other by screwing the closures onto and off from the tubular member 6 and then securing the 80 closures in adjusted position by set screws 30 passed through the flange of the closures and engaging with the screw threads on the member 6.

To connect the coils of the solenoids 19, 20 85 in circuit with an electric oscillation receiving circuit to be influenced thereby and actuate the diaphragms one terminal 31 and 32 of each coil is connected to a contact member carried by and insulated from the 90 casing member 6, said contacts comprising shouldered tubular members 33 inserted into and insulated from openings in the member 6 to which the coil terminals 31, 32 are connected by set screws 34 threaded into the 95 contact and soldering, the said screws being in the nature of binding posts and also serving to retain contact plugs 35 connected to the conductors of the electric oscillation receiving circuit and inserted into the openings in the contacts 33.

While I have illustrated the invention as embodying a pair of diaphragms, it will be obvious that only one diaphragm may be utilized, and that in the use of the two diaphragms each of the closures may be arranged for the connection of a sound amplifying horn thereto. Furthermore, various modifications may be made in construction and arrangement of parts and portions of 100 the invention may be used without others and come within the scope of the invention.

While I have illustrated and described the invention as being particularly applicable for the transforming of electrical oscillations into audio oscillations wherein the diaphragm or diaphragms are actuated by magnetic means influenced through the variations in the electric oscillations, it is to be understood that the same is applicable to 115 sound boxes of sound reproducing machines by connecting the stylus carrier to one diaphragm and where more than one diaphragm is utilized interconnecting the diaphragms so that all of the diaphragms will 120 be vibrated in unison through the actuation of the one diaphragm by the stylus carrier.

Having thus described my invention, I claim:

1. In a transformer of electric oscillations 130

- into audio oscillations, a casing having an opening, magnetic means mounted in fixed position in the casing adapted for connection in circuit with and influenced by an electric oscillation receiving circuit, a diaphragm, a closure for the casing opening having a central perforation to constitute an outlet for the casing and arranged for mounting of the diaphragm thereon in operative relation to the magnetic means to be actuated thereby and with an air space around the same in communication with the casing outlet, and said closure having an adjustable connection with the casing whereby the magnetic means and diaphragm are adapted to be variably adjusted one relative to the other.
2. In a transformer of electric oscillations into audio oscillations, a tubular member, magnetic means mounted in said member adapted for connection in circuit with and influenced by an electric oscillation receiving circuit, a pair of diaphragms, a closure for each end of the tubular member one of said closures having a central aperture, said closures co-operating with the tubular member to provide a casing to which the aperture in the one closure serves as an outlet and arranged for the mounting of the diaphragms thereon with the magnetic means interposed between and in operative relation to the diaphragm to vibrate the diaphragms in unison by variations induced in the magnetic field generated by the magnetic means through oscillations in the current flow of the electric oscillation receiving circuit, and said closures having an adjustable connection with the tubular member whereby the diaphragms are adapted to have variable adjustment relative to each other and the magnetic means one independent of the other.
3. A transformer of electric oscillations into audio oscillations as claimed in claim 2 wherein the diaphragms are arranged with an air chamber extending around opposite sides of the diaphragms and in communication with the outlet of the casing.
4. In a transformer of electric oscillations into audio oscillations, an open end casing, magnetic force generating means mounted in the casing adapted for connection in circuit with and influenced by an electric oscillation receiving circuit, a closure for the open end of the casing having an opening arranged for the connection of sound amplifying means adjustably mounted on the casing, and a diaphragm mounted on the closure with the closure opening in communication with an air space at opposite sides of the diaphragm and adapted to be variably positioned by the closure in operative relation to the magnetic force generating means to be actuated thereby.
5. In a transformer of electric oscillations into audio oscillations, an open end casing, magnetic force generating means mounted in the casing adapted for connection in circuit with and influenced by an electric oscillation receiving circuit, a closure for the open end of the casing having a sound emitting opening, adjustably mounted on the casing, said closure having lugs extending laterally from the inner face, a diaphragm, and means for mounting the diaphragm on the lugs on the interior of the closure said lugs being constructed and arranged to position the diaphragm in operative relation to the magnetic force generating means and provide a space at both sides of the diaphragm in open communication with the sound emitting opening.
6. In a transformer of electric oscillations into audio oscillations, an open end casing, magnetic force generating means mounted in the casing adapted for connection in circuit with and influenced by an electric oscillation receiving circuit, a closure having an adjustable connection with the open end of the casing and a sound emitting opening, and a diaphragm mounted and carried on the inner side of the closure arranged when the closure is connected to the casing to provide an air space at opposite sides of the diaphragm in open communication with the sound emitting opening in the closure.
7. In a transformer of electric oscillations into audio oscillations, a casing comprising a tubular member and a closure connected to the opposite ends of said member and one closure arranged with a sound emitting opening, magnetic force generating means mounted in the casing intermediate the ends adapted for connection in circuit with and influenced by an electric oscillation receiving circuit, and a diaphragm mounted and carried on the inner side of each closure arranged when the closures are connected to the tubular member to provide an air space at opposite sides of each diaphragm in open communication with the sound emitting opening in the one closure and the diaphragms adapted to be positioned by the closures in variable operative relation to said magnetic force generating means to be actuated thereby.
8. A transformer of electric oscillations into audio oscillations as claimed in claim 7, wherein the magnetic force generating means comprises a permanent magnet and a pair of coils with the core of the one coil constituting a pole piece connected to one pole of the permanent magnet and the core of the other coil constituting a pole piece connected to the other pole of the permanent magnet.
9. In a transformer of electric oscillations into audio oscillations, a casing including a tubular member with disk closures for the opposite ends having threaded flanges for threaded connection with said member one

- of said closures having an opening to constitute an outlet for the casing and lugs extending laterally from the inner side thereof, a ring form permanent magnet, pole
5 pieces connected to the poles of the magnet arranged to position the pole pieces within the magnet and the terminals of the pole pieces to extend in parallel relation transversely of the magnet, electromagnetic force
10 generating means mounted on said pole piece, a diaphragm, and means to mount the diaphragm upon the closure lugs whereby the casing outlet is in communication with an air space within the casing extending
15 around both sides of the diaphragm.
10. A transformer of electric oscillations into audio oscillations as claimed in claim 9, wherein each of the closures is arranged with lugs extending laterally from the inner
20 side thereof for the mounting of a diaphragm upon each of the closures with the

casing outlet in communication with an air space in the casing extending around both sides of each diaphragm.

11. A transformer of electric oscillations 25 into audio oscillations as claimed in claim 9, wherein the electromagnetic force generating means comprises a pair of coils one mounted on each pole piece.

12. In a transformer of electric oscillations 30 into audio oscillations as claimed in claim 9, contact terminals mounted on and insulated from the tubular member of the casing adapted for electrical connection of the magnetic force generating means and 35 for connection of electric current conductors exterior of the casing.

Signed at New York city, in the county of New York and State of New York, this 6th day of August, 1925.

JOHN E. DAVIS.
